UNITED STATES PATENT OFFICE.

WILLIAM D. KYLE, OF MILWAUKEE, WISCONSIN, ASSIGNOR TO LINE MATERIAL COMPANY, OF SOUTH MILWAUKEE, WISCONSIN, A CORPORATION OF WISCONSIN.

CUSHION-HEAD INSULATOR PIN.

Application filed November 15, 1922. Serial No. 601,067.

To all whom it may concern:

Be it known that I, WILLIAM D. KYLE, a citizen of the United States, and resident of Milwaukee, in the county of Milwaukee and State of Wisconsin, have invented new and useful Improvements in Cushion-Head Insulator Pins, of which the following is a description, reference being had to the accompanying drawings, which are a part of this specification.

The invention relates to insulator pins.

The object of this invention is to provide an insulator pin of simple and economical construction in which a soft metal wire forms a thread to receive the insulator and acts as a cushion to prevent cracking of the insulator when screwing it onto the pin member or when the pin member itself contracts and expands in service.

20 The invention further consists in the several features hereinafter set forth and more particularly defined by claims at the conclusion hereof.

25 In the drawings: Fig. 1 is an elevation view of an insulator pin embodying the invention; Fig. 2 is a vertical sectional view through the head of the pin; Fig. 3 is a top view of the pin, and Fig. 4 is a detail view of a wire forming the thread.

30 In the drawings the numeral 5 designates a metal pin member having a shank portion 6 threaded at its outer end 7, and a conical or tapered head portion 8 provided with threads 9. The shank portion 6 is provided 35 with a boss or flange portion 10 having a wrench-engaging part 11. The shank below the portion 10 is adapted to be worked down through an opening 12 in a cross-arm 13, or

other suitable support, and the pin is then secured by a clamping engagement with said arm by the portion 10 and a clamping nut 14.

A wire, such as the wire 15, made of soft metal, such as lead, or the wire shown in Fig. 4, having a relatively hard metal wire 16 forming a core and a soft metal covering 17, is adapted to be wound around the threads 9 to form threads engaged by the insulator 18.

In each instance, and more particularly 50 shown in Fig. 2 in connection with wire 15, the ends of the wire are anchored in the head by inserting them in transverse holes or recesses 19.

By the term "soft metal" wire as used 55 in the claims, I mean either a wire consisting entirely of soft metal or one having a soft metal covering.

What I claim as my invention is:

1. In an insulator pin, the combination, 60 with a pin member provided with a tapered threaded head, of a soft metal wire seated in the grooves formed by said threaded head and projecting therefrom to form threads for the insulator, said member having transversely extending recesses in the head receiving the ends of said wire.

2. In an insulator pin, the combination, 70 with a pin member provided with a tapered threaded head, of a soft metal wire having a hard metal core and mounted on said head to form threads for the insulator.

In testimony whereof, I affix my signature.

WILLIAM D. KYLE.
